CLAIM

We claim the ornamental design for a stand for television receiver, as shown and described.

DESCRIPTION

FIG. 1 is a front perspective view of a stand for television receiver showing our new design;

FIG. 2 is a rear perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is a bottom plan view thereof;

FIG. 9 is a front perspective view of the stand for television receiver showing environmental subject matter; and,

FIG. 10 is another front perspective view showing alternate environmental subject matter.

The broken lines shown in FIGS. 1 to 8 represent portions of the stand for television receiver that form no part of the claimed design. The broken lines showing of the display screen in FIGS. 9 and 10 is for the purpose of illustrating environment and form no part of the claimed design.

1 Claim, 10 Drawing Sheets
